DESIGN FOR A PARER OR SIMILAR ARTICLE

Fred Wisser, Elmhurst, N. Y.

Application July 22, 1936, Serial No. 63,976

Term of patent 14 years

To all whom it may concern:

Be it known that I, Fred Wisser, a citizen of Germany, residing at Elmhurst, in the county of Queens and State of New York, have invented a new, original, and ornamental Design for a Parer or Similar Article, of which the following is a specification, reference being had to the accompanying drawing, forming part thereof.

In the drawing:

Fig. 1 is a front elevation of a parer or similar article, showing my new design;

Fig. 2 is an edge view thereof, and
Fig. 3 a rear view of the parer.

I claim:

The ornamental design for a parer or similar article, as shown.

FRED WISSE.
